ADDISON B. CARL, OF BOOTHWYN, PENNSYLVANIA.

RATCHET MECHANISM FOR TOOLS.

1,138,277.

Specification of Letters Patent.

Patented May 4, 1915.

Original application filed May 24, 1913, Serial No. 769,646. Divided and this application filed April 15, 1914. Serial No. 832,060.

To all whom it may concern:

Be it known that I, ADDISON B. CARL, a citizen of the United States, residing at Boothwyn, in the county of Delaware and State of Pennsylvania, have invented a new and useful Ratchet Mechanism for Tools, of which the following is a specification.

The invention relates to improvements in ratchet mechanism for tools, and is a division of an application filed by me May 24, 1913, Serial No. 769,646.

The object of the present invention is to improve the construction of ratchet mechanisms, and to provide a simple, efficient, and comparatively inexpensive ratchet mechanism, designed for use on various kinds of tools, such as ratchet wrenches, ratchet drills, ratchet braces, etc., and equipped with a reversible pawl having an engaging portion arranged to be wedged between a ratchet wheel and a coacting oscillatory member, so that the strain or pressure incident to the operation of the tool on the working stroke will maintain the pawl in engagement with the ratchet wheel and prevent any liability of the pawl accidentally slipping inwardly or backwardly.

With these and other objects in view the invention consists in the construction and novel combination of parts hereinafter fully described, illustrated in the accompanying drawing, and pointed out in the claims here-to appended, it being understood that various changes in the form, proportion, size, and minor details of construction, within the scope of the claims, may be resorted to without departing from the spirit or sacrificing any of the advantages of the invention.

In the drawing:—Figure 1 is a longitudinal sectional view of a ratchet mechanism constructed in accordance with this invention. Fig. 2 is a longitudinal sectional view taken at right angles to Fig. 1. Fig. 3 is a sectional view showing the reversible pawl at its central position, in engagement with the recess of the rotary stock or shank. Fig. 4 is a transverse sectional view on the line 4—4 of Fig. 1. Fig. 5 is a sectional view on the line 5—5 of Fig. 3.

Like numerals of reference designate corresponding parts in all the figures of the drawing.

In the accompanying drawing, in which is illustrated the preferred embodiment of the

invention, 1 designates an oscillatory operating member having an enlarged terminal portion 2, provided with an aperture consisting of a substantially circular or segmental outer portion 3, and an approximately rectangular inner portion 4. The outer portion 3 of the aperture is greater than a semi-circle to provide a curved wall 5 for embracing and forming a bearing for a ratchet wheel 6, which may be formed by cutting spur teeth in a rotary stock or shank 7, but the ratchet wheel may be applied to such stock or shank in any other preferred manner. The stock or shank 7 is provided at one side or face of the enlarged portion 60 of the oscillatory member with a projecting annular enlargement or collar 8, which forms a shoulder to fit against the adjacent side of the oscillatory member. In the accompanying drawing, the ratchet mechanism is adapted particularly for use on ratchet braces, and the stock or shank 7 is provided to be provided at its outer end with the usual tool receiving socket or head (not shown), but the rotary stock or shank may 65 be of any preferred construction, to suit the character of the tool to which the ratchet mechanism is to be applied. The stock or shank is retained in the outer portion of the aperture of the oscillatory member by a nut 9, adjustably mounted on a reduced portion 70 10 of the stock or shank having screw threads 11. The member 1 is oscillated in the usual manner in the operation of the tool, and the enlarged end 2 is arranged 75 between the flat faces of the collar 8 and nut 9. The flat faces of the collar 8 and nut 90 86 85 86 85 90 95 100 105 110 115

The ratchet wheel 6 is engaged by a reversible pawl 12 consisting of a circular head or disk 13 having an engaging portion 14 and a central longitudinal stem or pivot 15 extending into a longitudinal opening 16 of the handle and slidable therein to carry the engaging portion of the pawl into and out of engagement with the ratchet wheel, and capable also of rotary movement to reverse the pawl for arranging the engaging portion thereof at either side of the enlarged terminal of the oscillatory member. The longitudinal opening 16 of the oscillatory member has a counter-bore 17 which receives a coiled spring 18, bearing at its lower end against the disk or head of the pawl, and having its inner end seated against the shoulder 19, formed by the counterbore 17. The engaging portion 14 of the pawl 110

consists of an extension located at one side of the circular head or disk 13 and having straight parallel or flattened side faces and a straight inner edge or face. The outer 5 peripheral face of the enlargement is preferably smooth and curved, as shown. The enlargement is provided at the inner side with an inclined or angularly disposed series of teeth 20 extending entirely across the enlargement and having their points arranged 10 in an arc corresponding with the periphery of the ratchet wheel, and presenting flat faces to the teeth thereof and adapted to engage in the grooves or spaces between the 15 said teeth. While only two teeth 20 are shown in the accompanying drawing, the number may be varied, and the pawl may be equipped with three teeth, as illustrated in the aforesaid application. The angularly disposed series or sets of teeth form 20 a tapered outer engaging portion with the terminal thereof tapered inwardly at the outer tooth, the flat engaging face thereof being set at an acute angle to the longitudinal axis of the oscillatory member. By this 25 construction the tendency of the ratchet wheel is to draw the pawl around with it, whereby the strain or pressure on the said pawl in the vertical movement thereof serves 30 to wedge the pawl between the ratchet wheel and the adjacent side of the oscillatory member. This action of the parts maintains the pawl securely in engagement with the ratchet wheel and effectually prevents the 35 pawl from accidentally slipping or springing out of such engagement. The circular head of the pawl operates in the inner approximately rectangular portion of the aperture of the oscillatory member, and it extends entirely across the said aperture and 40 projects from the opposite or side face of the oscillatory member, whereby it may be operated at either side of the same. The inner faces 22 of the enlarged terminal portion of the oscillatory member at the rectangular portion of the aperture are curved transversely and present smooth surfaces to the head of the pawl. When the member 1 is oscillated in the vertical movement of 45 the tool, it is locked rigid with the stock or shank by the action of the pawl, and when the said member is swung in the opposite direction, the pawl releases the ratchet wheel and ratchets over the teeth of the same, and 50 permits the said member 1 to turn independently of the stock or shank. The pawl has a slight reciprocation in engaging and releasing the ratchet wheel, and it is guided in such reciprocation and held against 55 rotary movement by the annular shoulders formed by the collar 8 and the nut 9 of the stock. The pawl is moved inwardly or rearwardly to carry its engaging portion out of engagement with the annular shoulders of 60 the stock when it is desired to partially ro-

tate the pawl for reversing the ratchet mechanism. The outer circular portion 3 of the aperture of the enlarged terminal portion of the oscillatory member 1 is of greater diameter than the inner rectangular portion 4 of the said aperture, and when the oscillatory member is separated from the stock or shank, the pawl may be readily moved into and out of the said outer portion 3 of the aperture, and be thereby detached from the 70 said member 1. This construction will enable the parts to be readily separated and assembled.

The annular enlargement or collar 8 of the stock or shank 7 is provided at its shoulder with a substantially oblong recess 25, of a size to receive the projecting engaging portion of the reversible pawl when the latter is in a central position, as illustrated in Figs. 3 and 5 of the drawing. The engaging portion of the pawl is preferably reduced in width at its outer portion, as indicated at 24, and the bottom of the recess 25 is curved to conform to the configuration of the peripheral face of the engaging portion of the pawl. The flat side faces of the reduced outer portion of the said engaging portion of the pawl are adapted to fit against the end walls of the recess 25, and the oscillatory member is interlocked with the stock or shank and the two parts are held against relative rotary movement when the pawl is in engagement with the recess 25. The inner portion 26 of the oscillatory member is tubular and interiorly threaded to receive a terminal portion 27 of a tubular handle member or brace 28, but the oscillatory operating member 1 may be connected with any other suitable means for enabling it to be oscillated.

What is claimed is:

1. A ratchet mechanism of the class described including a rotary stock or shank having a ratchet wheel, an oscillatory operating member having a bearing receiving the said ratchet wheel, and a rotary reversible pawl carried by the operating member and provided with an eccentrically arranged engaging portion adapted to be carried to either side of the bearing of the said member by the rotary movement of the pawl, said engaging portion being constructed to interlock with the teeth of the ratchet wheel, and the metal of the engaging portion being arranged to be clamped and wedged between the ratchet wheel and the operating member at the adjacent side of the bearing to lock the pawl in engagement with the ratchet wheel.
2. A ratchet mechanism of the class described including a rotary stock or shank having a ratchet wheel, an oscillatory operating member having a bearing opening and receiving the ratchet wheel, and a rotary reversible pawl carried by the operating

member and provided with a tapered engaging portion, said engaging portion being eccentrically arranged so as to be carried to either side of the bearing by the rotary movement of the pawl, whereby the tapered engaging portion will be clamped or wedged between the ratchet wheel and the adjacent side of the bearing.

3. A ratchet mechanism of the class described including a rotary stock or shank having a ratchet wheel, an oscillatory operating member provided with an aperture receiving the ratchet wheel, and a spring actuated pawl carried by the operating member and mounted for rotary movement thereon, said pawl being provided with an eccentrically arranged engaging portion having an arcuate series of ratchet teeth to be carried to either side of the aperture by the rotary movement of the pawl, the metal of the teeth being arranged to be clamped between the ratchet wheel and the adjacent side wall of the said aperture.

4. A ratchet mechanism of the class described including a stock or shank having a ratchet wheel and provided with an aperture receiving the ratchet wheel, and a spring actuated pawl mounted for rotary movement on the said operating member and provided with a tapered eccentrically arranged engaging portion having an arcuate series of teeth adapted to be carried to either side of the said aperture by the rotary movement of the pawl, the terminal teeth being tapered inwardly and interlocking with the ratchet wheel and adapted to be clamped between the same and the adjacent side wall of the said aperture.

5. A ratchet mechanism of the class described, including a stock or shank provided with a recess, a ratchet wheel carried by the

stock or shank and located adjacent to the recess, an operating member having an aperture receiving a ratchet wheel, and a reversible pawl mounted for rotary movement on and carried by the operating member and having an eccentrically arranged engaging portion, said engaging portion being adapted to be carried to either side of the operating member by the rotary movement of the pawl and being also adapted, when in an intermediate position, to engage the said recess to lock the operating member rigid with the stock or shank.

6. A ratchet mechanism of the class described including a stock provided with a ratchet wheel and having spaced shoulders, an operating member having an aperture receiving the ratchet wheel and provided with an adjoining aperture, a spring actuated pawl located in the said adjoining aperture of the operating member and including a rotary head extending through and beyond the side face of the operating member, said head having a central guiding spindle with a spring on one side and a flat tapered eccentrically arranged engaging portion with an arcuate series of teeth on the other side, said engaging portion being arranged to reciprocate between the said shoulders of the stock and adapted to interlock with the ratchet wheel, and the metal of the tapered engaging portion being arranged to be clamped between the ratchet wheel and the adjacent side wall of the aperture.

In testimony, that I claim the foregoing as my own, I have hereto affixed my signature in the presence of two witnesses.
